GAME APPARATUS

Fred C. Steffens, Chicago, Ill., assignor, by mesne assignments, to Chicago Patent Corporation

Application May 22, 1936, Serial No. 81,194

13 Claims. (Cl. 273—121)

This invention relates to game apparatus and particularly to game apparatus in which a successful player is rewarded by an appropriate number of free games.

5 The invention is particularly concerned with a device for recording and controlling the number of games available to the player and has for its principal object the provision of an improved control mechanism for these purposes.

10 A further object of the invention is to provide a control apparatus which is simple in construction and operates rapidly with efficiency, speed and with very little noise.

15 Other objects, advantages and capabilities of the invention will appear from the following description of a preferred embodiment thereof, taken in conjunction with the accompanying drawings, in which:

20 Figure 1 is a plan view of a game apparatus embodying my invention;

Fig. 2 is a fragmentary sectional view on a larger scale, taken on the line 2—2 of Fig. 1;

Fig. 3 is a plan view of my improved control device;

25 Fig. 4 is a side elevation thereof, as viewed from the right-hand side of the game apparatus;

Fig. 5 is a side elevation, as viewed from the opposite side;

Fig. 6 is a sectional view, taken on the line 6—6 of Fig. 5;

Fig. 7 is a fragmentary detail, and

Fig. 8 is a wiring diagram showing parts of the control apparatus in perspective.

Referring to the drawings, the invention is illustrated in connection with a game of the so-called "pin game" type. It must be understood, however, that the invention is not intended to be limited to games of this particular type, or to the particular game which is illustrated. It may be applied equally well to any game in which the attainment of the objective can be arranged to close a control switch.

The game apparatus illustrated in the drawings comprises a cabinet 10, the upper face of which 45 consists of a window 11. Beneath this window is located the playing board or field 12 which slopes downwardly towards the front end of the apparatus. The playing board 12 is provided with suitable openings 13 into which the player 50 endeavors to roll the balls 14. Beneath the playing board 12 is slidably mounted a board 15 which is normally held in its forward position, shown in Fig. 2, by means of springs (not shown). In this forward position the board 15 provides a support for the balls 14 which may enter any of

the holes 13. Beneath each of the holes 13 the board 15 carries a pair of resilient members 16 which are normally out of contact. When a ball 14 enters one of the openings 13 it depresses one of the resilient members 16 into contact with the other resilient member 16, as shown in Fig. 2. Thus, each pair of resilient members 16 constitutes a switch. For ease of reference, these switches are designated S2, S4, S6, S10 and S20, the numerical portion of these reference numerals corresponding to the number of free games provided by the attainment of the objective of locating a ball in that particular opening.

When the board 15 is pushed rearwardly by 15 means of a lever 17, as will hereinafter be described, openings 18 in the board 15 are brought into alignment with the openings 13, allowing the ball or balls located in the openings 13 to fall 20 downwardly onto a board 19.

Board 19 allows the balls to roll downwardly into a chute 20 from which they may be elevated by a ball elevator 21 into a chute 22 on the right-hand side of the playing board. A ball 14 thus elevated can be projected upwardly by means of 25 an impeller 23 in known manner. The ball thus played may, according to the skill of the player, be directed into any particular one of the openings 13. The board 12 is provided with suitable obstructions 24 to render the locating of the ball 30 in any particular hole 13 very difficult, depending upon the numerical value of each particular hole. When the player has played the ball or balls, the game is terminated until the board 15 is again moved forwardly by the lever 17.

35 The lever 17 is pivotally mounted on the frame 25 of the control device, the upper end of the lever 17 which engages the board 15 being shown in the right-hand top corner of Fig. 4. To this lever is pivotally secured a rearwardly extending lever 26. The pivot 27 of the lever 26 extends outwardly, as shown in Fig. 4, and passes through a slot 28 of a link 29. The link 29 is pivotally connected to a lever 30 which is pivotally mounted on the frame 25 by means of a stud 31. The lower end of the lever 30 is pivotally connected to a link 32 and this link is in turn pivotally connected to a rack 33. The rack 33 slides on a shelf 34 carried by the frame 25 and cooperates with a pinion 35 which is pinned to or otherwise rigidly 40 mounted upon a shaft 36.

45 The shaft 36 is horizontal and is rotatably mounted in bearings provided by the frame 25. The shaft 36 freely carries a dish-like drum 37 and a ratchet wheel 38, suitably located within 50

the dish-like drum 37 and rigidly secured thereto. A commutator which may suitably comprise a cylindrical member 39 of wood or other insulating material and a sheet of conductive material 40, configured in accordance with the requirements of the control apparatus, is rigidly mounted on the shaft 36, but is adapted to be latched to the drum 37 during the operation of the device, as will hereinafter be described.

10 The lower end of the lever 30 is secured to a tension spring 41, the other end of which is secured to a bracket 42 carried by the frame 25. It will be noted that the tension of the spring 41 will normally tend to move the rack 33 to the right, as viewed in Fig. 4, thus tending to cause the drum 37, together with the commutator and the ratchet 38, to move in the counter-clockwise direction, as viewed in that figure. The shelf 34 carries a pin 43 which extends upwardly into a longitudinal slot 44 in the rack 33 so as to maintain the rack against lateral displacement out of engagement with the pinion 35. The lever 17 has attached thereto a forwardly extending link 45 which is slidably supported by means of a screw 46 carried by the frame 25. The link 45 is engaged by a full stroke pawl 47 which insures the complete rearward movement of the lever 17 when actuated. The lever 17 is pulled forwardly by a spring 48 connected to this lever and also to the frame 25. If desired, this spring may be omitted and the contact of the board 15 with the upper end of the lever 17 may be relied upon to move the lever 17 to its forward position, the board 15 being normally held in its forward position by means of springs (not shown).

The rearwardly extending lever 26 comprises a laterally extending flange 49 from which depend two projections 50 and 51. These projections are in alignment with the coin slide 52 and one or other of them is adapted to be engaged by the coin slide when that element is moved rearwardly. Whether one or the other of the projections 50 or 51 is engaged by the coin slide depends upon the condition of elevation of the lever 26. This lever has two positions, shown in full and dotted lines in Fig. 4. In the full line or elevated position of the lever 26 the coin slide is arranged so that it passes below the projection 50 and engages the projection 51. When the lever 26 is in its dotted line position the coin slide engages the projection 50. The projection 50 is closer to the front of the apparatus than is the projection 51 and, consequently, in the latter case the coin slide need only be pushed inwardly 55 to a comparatively small extent to effect the movement of the lever 17 to start a game.

The lever 26 carries near its forward end a flange 53. When the lever 26 is in its lowermost position; that is, the dotted line position as shown in Fig. 4, the flange 53 slides upon a horizontal part of the frame 25. The lever 26 carries a pin 54 which is adapted to engage an upstanding hook member 55 carried by the frame 25 when the lever 26 is moved rearwardly by the engagement of the coin slide 52 with the projection 50. This engagement between the pin 54 and the hook member 55 prevents the coin slide from being moved rearwardly to the extent of removing the coin from the coin slide. In other words, the low position of the lever 26 corresponds to a free game.

The lever 26 is elevated into its full line position, as shown in Fig. 4, by means of a bracket 56 carried by the ratchet 38 in one particular position. This position corresponds to the initial

condition of the apparatus in which no free games are available to the player. To initiate playing, the player must insert a suitable coin in the coin slide 52 and he must push the coin slide inwardly to its full extent in order that the coin slide 52 may engage the projection 51 and effect the rearward movement of the board 15 to render available the ball or balls with which the game is played. If the player succeeds in making his objective, the drum 37 and ratchet wheel 38 are 10 rotated in counter-clockwise direction, as viewed in Fig. 4, to a suitable extent, depending upon the value of the objective attained. However, irrespective of the value of the objective the bracket 56 is moved out of contact with the flange 53 15 of the lever 26 so that the apparatus is now operable as a free game apparatus until, owing to the loss of games, the bracket 56 again elevates the lever 26.

The drum 37 is normally held against rotation 20 in the counter-clockwise direction (as viewed in Fig. 4) by means of a dog 57. The lower end of the dog 57 is formed into a stirrup-like member 58 which serves as an armature for an electromagnet 59. Thus, with reference to Figs. 4 and 25 5, it will be understood that when the magnet 59 is energized the dog 57 is drawn out of contact with the ratchet wheel 38 and this ratchet wheel, together with the drum 37 and the commutator 39, are rotated in the counter-clockwise 30 direction, as viewed in Fig. 4. As will hereinafter be described, this counter-clockwise rotation of the commutator 39 breaks the circuit which energizes the magnet 59, and when this occurs the dog 57 moves back into engagement with the 35 ratchet wheel 38 under the influence of the spring 59a.

Referring now particularly to Figs. 5, 6 and 7, it will be noted that the drum 37 rigidly carries on its face adjacent the commutator 39, a 40 disc 60 which is provided around its periphery with a series of slots 61. The commutator 39 carries a radial arm 62, the end of which is bent outwardly to provide a flange 63. Upon this flange is pivotally mounted a pawl 64, one end 45 of which is adapted to enter any of the slots 61 so as to latch the drum 37 and commutator 39 rigidly together. The latch 64 is normally biased towards the disc 60 by means of a spring 65, shown in Fig. 7. The pawl 64 carries a pin 66 which is 50 adapted to engage a cam member 67 carried by the frame 25. When the commutator 39 is rotated in the counter-clockwise direction, as viewed in Fig. 5, with relation to the drum 37, the pawl 64 slips over the slotted periphery of the disc 60 55 and when it reaches its final position the pin 66 engages the surface of the cam 67 which throws the pawl 64 into unlatched position.

The pawl 64 carries a projection 68 which is 60 adapted to be engaged by a latch 69, best shown in Fig. 5. This latch is pivotally mounted on the frame 25 and is normally biased towards the position shown in that figure by the spring 70. The latch 69 comprises an inwardly turned portion 71 which extends below the armature 58. 65 It will thus be seen that when the magnet 59 is energized, the dog 57 is released and also the pawl 64. Owing to the release of the dog 57, the spring 41 effects the rotation of the drum 37 in the counter-clockwise direction as viewed in Fig. 4, and in the clockwise direction as viewed in Fig. 5. Owing to the release of the pawl 64, the spring 65 is enabled to draw the pawl into operative contact with the adjacent slot 61 of the disc 60. Consequently, the commutator is 70

latched to the drum 37 and is carried around therewith during the rotation referred to.

The control apparatus is arranged near the forward end of the cabinet as shown in Fig. 1, and a window 92 is provided whereby one of a series of numbers provided on the flange of the drum 37 may be viewed by the player. The ratchet wheel 38 is provided with a projection or stop 93 which is adapted to engage a stop 94 on the frame 25 when the ratchet wheel 38 is moved into the position shown in Fig. 4, which is the position corresponding to the beginning of play. Near its forward end the lever 26 carries a projection or tooth 95 which extends laterally over the ratchet wheel 38 so that it may engage the teeth of this wheel in the manner hereinafter described. The commutator drum 39 is provided with a projection 96 which is adapted to engage and close the switch 81 in the event of the excessive rotation of the commutator. The effect of the closing of this switch is to energize the electromagnet 85 which opens the switch 87 and throws the apparatus out of operation until the coin slide 52 is pushed rearwardly again. The rearward movement of the lever 26 effecting the return of the commutator to its initial position. The switch 82 is adapted to be closed by a stop 97 on the interior of the drum 37. In the event that drum 37 is rotated excessively in the counter-clockwise direction, as viewed in Fig. 4, the switch 82 closes with the result that the main switch 87 is opened.

As has heretofore been indicated, the commutator comprises a cylindrical block of insulating material upon which is located the conductive sheet 40. At one end the sheet 40 extends across the face of the commutator and this part of the sheet 40 is in contact with the brushes B2, B4, B6, B10, B20, and BB at the beginning of play, as shown in Fig. 8. These brushes are preferably mounted in a row upon a strip of insulation 72. The brushes B2, B4, B6, B10 and B20 are connected by wires 73, 74, 75, 76 and 77 to one side of the corresponding switches S2, S4, S6, S10 and S20, as shown in Fig. 8. The other contacts of these switches are connected by a common wire 78 to one end of the electromagnet 85. The other end of the electromagnet is connected to a battery 79 and also to a wire 80. The wire 80 is connected to one side of the switch 81, a switch 82 and one side of a switch 83 which is closed if any attempt is made to tilt the machine. The switch 83 may consist of a pendulum mounted within a ring. The other end of this switch is connected in series to the other end of the switches 81 and 82 by a wire 84 which is connected to the electromagnet 85. The other end of the electromagnet 85 is connected by a wire 86 to the brush BB. The wire 86 is connected to one side of a switch 87 which is adapted to be opened by the energization of electromagnet 85. The other side of the switch 87 is connected by a conductor 88 to the other side of the battery 79. The switch 87, which is shown diagrammatically in Fig. 8, comprises a latch 89 and is adapted to be closed by a rod 90 against the action of a spring 91. The rod 90 may be carried by the board 15 so that the switch 87 is closed when the coin slide is moved forwardly at the beginning of each game.

The correlation of the various parts of the machine will be readily understood from the following description of its operation. At the beginning of playing the apparatus normally has the drum 37 in its initial position. The flange of this

drum is provided with a series of indicia and the numeral "0" is visible through a window 92, as shown in Fig. 1. The commutator is in the position shown in Fig. 5; that is, with the pawl 64 out of engagement with the disc 60 and the commutator held by the latch 69 against rotation under the influence of the spring 41. The lever 26 is in its uppermost position, as shown in full lines in Fig. 4, this position corresponding to the zero position of the drum 37. The switch 87 may be open or closed, depending upon whether or not the preceding game was terminated with or without an attempt to beat the game by tilting the machine. A stop 93, carried by the wheel 38, is in contact with a stop 94 on the frame 25 so that there is no possibility of rotating the drum 37 in the clockwise direction, as viewed in Fig. 4.

To start playing the player must place the appropriate coin in the slide 52 and push it inwardly. The coin slide 52 must be pushed inwardly to its fullest extent in order to engage the projection 51 of the lever 26. The rearward movement of this lever effects the rearward movement of the board 15 and allows the balls 14 to fall downwardly through the openings 18 onto the board 19, from whence they roll into the chute 20 and become available to the player.

The rearward movement of the board 15 effects, through the rod 90, the closing of the switch 87. During this rearward movement; that is, the initial rearward movement at the start of playing, the coin slide 52 extends below the projection 50 of the lever 26 and holds this lever in elevated position after it is moved rearwardly off the bracket 56. This rearward movement of the lever 26 in its elevated condition, prevents the projection 95 on the forward end of the lever 26 from engaging the ratchet wheel 38.

The player now plays one of the balls 14 and if he is successful in getting it into one of the openings 18, one of the switches on the board is closed. Let us assume that one of the switches S6 is closed. As a consequence of the closing of the switch S6, a circuit will be completed through battery 79, electromagnet 85, conductor 78, switch S6, conductor 75, brush BB, conductive sheet 40, brush BB, conductor 86, switch 87 and conductor 88 back to the battery. The completion of this circuit through the winding of the electromagnet 85 has the effect of moving the latch 89 away from the ratchet wheel 38 and the movement of the latch 69 away from the pawl 64. Consequently, the spring 41 acting through the rack 33 causes the rotation of the commutator in the counter-clockwise direction, as viewed in Fig. 4. As a result of this movement of the commutator, the pin 66 moves away from the cam surface 67 slightly so that the pawl 64 engages one of the slots 61 of the disc 60. This happens immediately after the commutator starts to move and the result is that the drum 37 is carried around with the commutator by the spring 41. This rotation of the commutator and drum 37 continues until the portion of the conductive sheet 40 in engagement with the brush BB runs off that brush and breaks the circuit.

The conductive sheet 40 is cut stepwise, as shown in Fig. 8, so as to control the number of free games accorded by any of the switches S2, S4, etc. In the particular instance under consideration, the circuit is broken when the drum 37 has moved to an extent corresponding to six free games; that is, corresponding to an angle of six ratchet teeth on the ratchet wheel 38. At this point the indicating numeral 6 appears in

the window 92. When the electromagnet 59 is deenergized by the interruption of the circuit, the latch 57 immediately engages the ratchet wheel 38 and arrests the rotation of the commutator and the drum 37. The commutator is left displaced, in the clockwise direction, from the position shown in Fig. 5. The bracket 56 is displaced in the counter-clockwise direction, as viewed in Fig. 4, from its position in that figure, with the result that the lever 26 moves to its lowermost position shown in dotted lines. Assuming that the game is a one-ball game, it is now terminated leaving the player entitled to six free games.

To start a new game the player pushes the coin slide 52 inwardly, with the result that it engages the projection 50, owing to the lever 26 being in its lowermost position. Consequently, the pin 54 slides below the hook 55 and the rearward movement of the coin slide 52 is limited so that it is impossible to move it sufficiently into the apparatus to effect the usual release and deposit of the coin located in it. As a result of the rearward movement of the lever 26 in its lowermost position, the projection 95 on this lever engages the ratchet wheel 38 and rotates it in the clockwise direction, as viewed in Fig. 4, to the extent of one tooth. This has the effect of rotating the drum 37 so that the next lowermost indicia, that is the number 5, appears in the window 92, corresponding to the utilization of one of the player's free games.

The rearward movement of the lever 26 effects the rearward movement of the lever 17, with the result that the board 15 is moved rearwardly so as to return the ball to the player. This rearward movement of the lever 17 also effects the rearward movement of the link 29, the pin 27 coming into engagement with the end of the slot 28. By means of the lever 30 and link 32, this movement forces the rack 33 forwardly, causing a rotation of the pinion 35 and commutator 39 in the clockwise direction, as viewed in Fig. 4. The engagement of the pawl 51 with the ratchet wheel 38 prevents this ratchet wheel from rotating in the same direction. In the latter part of the stroke of the lever 26, the projection 95 of the lever 26 does rotate the ratchet wheel 38 and the drum 37 through an angle corresponding to one tooth of the ratchet wheel, as has heretofore been indicated. It will be noted that the full rearward movement of the lever 26, which is insured by the full stroke pawl 47, effects the return of the commutator to initial playing position, the pawl 64 slipping over the slot 61 of the disc 60 until the pin 66 comes into contact with the cam surface 67, which effects the removal of the point of the pawl 64 from the disc 60. The latch 69 then engages the projection 68 of the pawl 64 and holds the same in the position shown in Fig. 5.

The player may now play another free game and if he is successful in attaining his objective, a further movement of the drum 37 in the clockwise direction, as viewed in Fig. 5, is effected. If, however, he is unsuccessful in attaining his objective, he must push the coin slide 52 rearwardly again which effects a movement of the index drum 37 in the opposite direction, decreasing the number of free games available to the player by one. Playing in this manner continues until the player has used up all his free games, and the drum 37 moves back to its zero position. When this occurs the lever 26 is elevated and a coin, if not previously placed in the coin slide 52,

has to be placed therein in order to resume playing.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. In a free game control device, a rotatably mounted contact member, means for tending to rotate the contact member in one direction, means for preventing said rotation, electromagnetic means in circuit with the contact member for actuating the rotation preventing means, a control member rotatable with the contact member from a position wherein it prevents the playing of free games to a position wherein free games are playable, a latch securing the contact member to the control member so that the contact member rotates the control member in said direction and rotates freely in the opposite direction, and means for disengaging the latch to permit independent rotation of the control member in said opposite direction.

2. A free game control device comprising a rotating means for indicating the number of free games to which the player is entitled, a ratchet rigid with said indicating means, means for moving said ratchet and indicating means step by step in one direction as free games are played, a rotatably mounted member, a contact carried thereby, latch means for connecting said rotatable member to the ratchet and indicating means for rotation therewith, a spring tending to rotate the contact carrying member and the indicating means and ratchet in one direction, a pawl normally holding said ratchet against said rotation, electromagnetic means for retracting said pawl, an electrical circuit including said contact and said electromagnet means whereby the movement of the ratchet and indicating means is terminated after a predetermined movement, and means for moving said ratchet and indicating means step by step, and for moving the contact member to its initial position at each step.

3. A free game control apparatus comprising a rotatably mounted commutator, a series of brushes cooperating therewith for different angular distances, a pinion rigidly connected to said commutator, a sliding rack in mesh with said pinion, a spring tending to move the rack and rotate the commutator in one direction, a ratchet, a pawl holding said ratchet against rotation in said direction, a latch for securing said commutator to the ratchet so that the commutator and ratchet rotate together in said direction when the ratchet is released, said latch being adapted to slip relatively to the ratchet when the commutator is rotated in the opposite direction, an electromagnet in series with said commutator adapted when energized to release the pawl, an indicating member rigid with said ratchet indicating the number of free games available, means movable for initiating a game and moving the indicating member one step, means having a lost motion connection therewith and connected to said rack for swinging the commutator to initial position, means for unlatching the latch in this position, a second latch releasable by the electromagnet for holding said commutator in initial position, and means on said ratchet for elevat-

ing the means movable for initiating a game at the zero position of the indicating means.

4. A game apparatus comprising a plurality of electrical circuits including switches each adapted to be closed by members operable in the playing of the game, a relatively movable contact system normally in said circuits and adapted to break the circuits seriatim by said relative movement, means for normally preventing said movement, electromagnetic means in said circuits for actuating the last said means to permit said movement, and means for setting the apparatus to permit a plurality of free games depending upon the degree of movement of said contact system.

5. A free game device for an amusement apparatus of the type which includes a playing board and ball operated switches, said free game device comprising a free game indicator movably mounted in proximity to the said playing board, control means actuated by the operation of one or more of said switches for moving said indicator in a direction away from its initial or zero position at each operation thereof, said control means including a device for moving the said indicator a plurality of steps at a single operation thereof, the number of said steps at each operation being determined by the particular one of the said switches operated by the said ball.

6. A free game device for an amusement apparatus of the type which includes a cabinet having an inclined playing board provided with ball-receiving pockets, and a ball-retaining member slidably mounted in the said cabinet below the said inclined playing board for temporarily retaining therein balls which enter into said pockets, said free game device comprising a free game indicator movably mounted in or adjacent to the said cabinet, control means actuated by a played ball entering one of the said pockets for moving the said indicator in a direction away from its initial or zero position at each operation thereof, said control means including a device for moving the said indicator a plurality of steps in a direction away from its initial or zero position at each operation thereof, the number of said steps at each operation being determined by the particular one of the said pockets the said ball enters, means for resetting the said free game indicator back into its initial position, means for moving the said ball-retaining member into ball-releasing position, and means for simultaneously operating both the said resetting means for the said free game indicator and the said means for moving the said ball-retaining member into ball-releasing position.

7. A free game device for an amusement apparatus of the type which includes a cabinet having an inclined playing board provided with ball-receiving pockets, and a ball-retaining member slidably mounted in the said cabinet below the said inclined playing board for temporarily retaining therein balls which enter into the said pockets, said free game device comprising a free game indicator movably mounted in the said cabinet, control means actuated by a ball entering one of the said pockets for moving the said indicator in a direction away from its initial or zero position at each operation thereof, said control means including a device for moving the said free game indicator a plurality of steps in a direction away from its initial or zero position at a single operation thereof, the number of said steps at each operation being determined by the particular pocket the said ball enters, means for

resetting the said free game indicator back into its initial position, means for moving the said ball-retaining member into ball-releasing position, means for simultaneously operating both the said resetting means for the said free game indicator and the said means for moving the said ball-retaining member, and means for preventing operation of the said means for moving the said ball-retaining member, and of the said resetting means for the said free game indicator, when the said free game indicator is in its initial or zero position.

8. A free game device for an amusement apparatus of the type which includes a cabinet having an inclined playing board provided with ball-receiving pockets, and a ball-retaining member slidably mounted in the said cabinet below the said inclined playing board for temporarily retaining therein balls which enter into the said pockets, said free game device comprising a free game indicator movably mounted in or adjacent to the said cabinet, control means actuated by a ball entering one of the said pockets for moving the said free game indicator in a direction away from its initial or zero position at each operation thereof, said control means including a device for moving the said free game indicator a plurality of steps in a direction away from its initial or zero position at a single operation thereof, the number of said steps at each operation being determined by the particular one of the said pockets the said ball enters, means for resetting the said free game indicator back into its initial position, means for moving the said ball-retaining member into ball-releasing position, and a manual control member movably mounted in a wall of the said cabinet for simultaneously operating both the said resetting means for the said free game indicator and the said means for moving the said ball-retaining member into ball-releasing position.

9. A free game device comprising a free game indicator, means for operating the indicator to indicating positions, and means for controlling the operating means whereby the indicator is moved in a single operation to a position to indicate a given plurality of free games, said controlling means comprising a switch operable by a game playing member and a circuit closed by the switch including a brush and a commutator segment movable by said indicator operating means and being of such length as to effect opening of the circuit upon movement of the indicator to a position indicating said given plurality of free games.

10. In a free game device a free game indicator, means for operating the indicator to free game indicating positions, an electric control means for initiating and arresting the movement of the operating means whereby the indicator is moved uninterruptedly to any one of a plurality of positions to indicate a particular plurality of free games, said control means comprising electric circuits each provided with a free game-predetermining switch adapted, when closed, to initiate the operation of the operating means whereby the indicator is moved to the position for indicating the number of free games predetermined by the operated switch, said switches being operable each by a game playing member, and a pair of cooperating electrical contacts for each circuit, said pair of contacts for the circuit of each operated switch being arranged to retain the circuit in closed relation during the movement of the indicator to the position.

- tion wherein it indicates the plurality of free games predetermined by the switch so operated by a playing member, one of said contacts of each pair being movable by said operating means and being of such length as to move out of contact with the cooperating contact upon movement of the indicator to the said free game indicating position for opening the corresponding circuit and arresting the movement of the operating means.
11. A free game device for use with game apparatus of the type provided with a playing member and a manually operable member provided with coin control means for rendering the playing member accessible to the player, said device comprising a free game indicator, actuating means for moving the indicator to free game indication positions, latching means for said indicator actuating means, said latching means being releasable to enable said actuating means to operate the indicator uninterruptedly through different ranges to predetermined free game indicating positions and provided with resilient means for restoring the latching means to latching position for arresting the indicator in any such free game indicating position, electrically operable latch releasing means, means controlled by said device when said indicator is in any free game indicating position to render said manually operable member effective to release a playing member for playing a plurality of free games successively independently of said coin controlled means, and means for controlling the movement of said indicator to different indicating positions comprising a plurality of normally open circuits each including said latch releasing means and each provided with a switch adapted to be operated by the playing member to close the corresponding circuit for effecting the actuation of said latch releasing means, and means individual to each circuit effective when a respective

circuit is closed to open the circuit upon movement of the indicator to a position indicating a predetermined number of free games.

12. A free game device comprising a free game indicator operable to a position for indicating a predetermined plurality of free games, means for operating the indicator, and means for controlling the operating means whereby the indicator is movable in each single operation to said indicating position, said controlling means comprising switch means operable by a game playing member, a circuit closable by said switch means upon said operation thereof, and means comprising a pair of normally engaged contact members in said circuit, one of which is operated by the indicator operating means to disengage the other for opening said circuit to arrest the movement of the indicator upon movement of the latter to said free game indicating position.

13. A free game device comprising a free game indicator operable to positions each for indicating a predetermined plurality of free games, means for operating the indicator to indicating positions, and means for controlling the operating means whereby the indicator is movable in each single operation to one of said positions, said controlling means comprising switches each adapted to be actuated by a game playing member for predetermined a plurality of free games, circuits each adapted to be closed by one of said switches upon actuation thereof by a game playing member, and means comprising a pair of normally engaged contact members in the closed circuit, one of which members is operated by the indicator operating means to disengage the other to arrest movement of the indicator upon movement of the latter to a position for indicating the number of free games predetermined by the actuated switch.
